United States Patent Office

Des. 192,242

Patented Feb. 20, 1962

192,242

AUTOMOBILE

Irvin W. Rybicki, Franklin, and Stanley R. Wilen, Royal Oak, Mich., assignors to General Motors Corporation, Detroit, Mich., a corporation of Delaware

Filed June 12, 1961, Ser. No. 65,542

Term of patent 7 years

(Cl. D14—18)

FIGURE 1 is a front elevational view of an automobile, showing our new design.

FIGURE 2 is a top plan view thereof.

FIGURE 3 is a fragmentary side elevational view thereof.

FIGURE 4 is a sectional view taken generally along the plane indicated by line 4-4 of FIGURE 1.

FIGURE 5 is a sectional view taken generally along the plane indicated by line 5-5 of FIGURE 1, and

FIGURE 6 is a perspective view thereof.

The dominant features of our design reside in the portions shown in full lines.

We claim:

The ornamental design for an automobile, substantially as shown and described.
